UNITED STATES PATENT OFFICE.

MARCUS P. FLACK, OF NEW YORK, N. Y.

TELEPHONE APPLIANCE.

No. 928,637.

Specification of Letters Patent.

Patented June 1, 1909.

Application filed December 18, 1908. Serial No. 467,838.

To all whom it may concern:

Be it known that I, MARCUS P. FLACK, a citizen of the United States, residing at New York, in the county of New York and State 5 of New York, have invented certain new and useful Improvements in Telephone Appliances, of which the following is a full, clear, and exact description.

This invention relates to appliances for use 10 with telephone transmitters, and has for its chief object to provide a simple and effective device for inclosing the mouthpiece of the transmitter in such manner that while the transmitter can be used in the ordinary way 15 escape of sound will be prevented, to the end that a person desiring to use the instrument may do so without others in the room hearing any part of the conversation.

In general terms, the invention consists in 20 the novel features of construction and combinations of elements hereinafter described, and more particularly set forth in the claims.

The preferred embodiment of the invention 25 is illustrated in the annexed drawing, in which:

Figure 1 shows the complete device in vertical longitudinal section, applied to a telephone transmitter. Fig. 2 is a front view. Fig. 3 is a detail view showing the air inlet 30 port and the closure for the same. Fig. 4 is a detail sectional view of the annular pneumatic cushion against which the user rests his face when speaking into the device.

A telephone transmitter of the ordinary 35 type is indicated by A.

B designates a supporting member made of sheet metal, preferably aluminum, tapering outwardly and having its smaller end fitting the rim of the telephone mouthpiece C 40 rather snugly. At its base the supporting member has an inwardly extending flange D, having its edge extending under the shoulder at the smaller end of the mouthpiece. To put the supporting member in place on the 45 instrument the mouthpiece is unscrewed and its threaded shank thrust through the opening in the flange, after which the mouthpiece is screwed back into position, thereby clamping the supporting member tightly and securely in place.

The sound collector and screen is shown at 50 E, and consists of a hollow member F, of aluminum, hard rubber, or other suitable material, substantially conical in form, having at its smaller end a slightly flaring extension G adapted to fit tightly the supporting mem-

ber B. The flare of extension G and the corresponding taper of the supporting member B, make it easy to put on the screen, and also to vary the tightness of the fit and take up 60 wear by sliding the screen farther on toward the head H at the base of the supporting member. As shown, the sound-collector and sound-screen is oval in form at its front, for better conformity to the contour of the face. 65

At the front or outer edge of the sound screen is an annular pneumatic cushion I, overhanging the front opening of the screen or collector, and provided with an elastic flange J which fits over the edge of the screen 70 and serves to hold the cushion securely in place. This cushion is also oval in form, and is provided with a suitable valve K through which it may be inflated.

For the purpose of admitting air into the 75 interior of the screen while in use, one or more air inlet apertures L, L, are provided each having an external swinging shutter or closure, as M, by which the apertures may be closed wholly or partially when desired. 80

The inside of the sound screen is lined with a sheet of celluloid N, or other suitable material capable of being easily kept clean as a sanitary precaution.

Extending inwardly over the edge of the 85 mouthpiece C, is an annular flap or flange O, of soft rubber, or other sound deadening or non-acoustic material, held between the lining N and the body of the sound screen, the purpose of said flap or flange being to diminish 90 the reflection of sound from the interior of the mouthpiece and to prevent the edge of the mouthpiece, and the connected parts, from being thrown into vibration by speaking into the device. 95

The method of using the device is simple. The user simply places his face over the sound collector and screen, and speaks in the ordinary tone of voice. The nose fits up in the pointed or smaller end of the front of the 100 collector, and the soft pneumatic cushion makes a fairly close fit with the face, with the result that no articulate sounds can be heard by other persons in the room. Ordinarily the fit between the cushion and the 105 user's face is not accurate and close enough to exclude all air, so that breathing is not made difficult, but if it should be, or if the user desires to speak for some time without interruption one or more of the air inlet 110 apertures may be opened, thus admitting air freely. Practical use of the device has

demonstrated that with the air inlets open sound which escapes therethrough is too confused or inarticulate to be understood by a listener.

5 The sound screen can be readily detached by pulling it off of the supporting member, leaving the latter in place and in no way interfering with the use of the telephone. The device is simple in construction and has been 10 found to be thoroughly effective for its purpose.

It is to be understood that the form herein specifically shown and described is merely the preferred embodiment of the invention, 15 and may be modified as to details of construction without departure from the proper scope and spirit of the invention as defined by the appended claims.

What I claim is:

20 1. A device of the kind described, comprising a supporting member adapted to encircle the mouthpiece of a telephone transmitter, having a flange adapted to fit under the mouthpiece, whereby the mouthpiece will 25 hold said member in position on the transmitter, a sound collector and screen removably fitting over the supporting member and supported thereby, and an annular cushion for the face carried by the said screen at its 30 outer edge, as set forth.

2. A device of the kind described, comprising a supporting member adapted to encircle the mouthpiece of a telephone transmitter, having an inwardly extending flange 35 adapted to fit under the mouthpiece, a sound collector and screen of substantially conical form having at its smaller end a tubular extension removably fitting the supporting member, an annular cushion at the outer 40 edge of the sound collector and screen adapted to fit closely the face of the speaker, said collector and screen being provided with one or more apertures for the admission of air, as set forth.

45 3. In a device of the kind described, a supporting member adapted to encircle the mouthpiece of a telephone transmitter, said member being tapered and having at its base an inwardly extending flange to fit under the 50 mouthpiece so as to be securely clamped thereby on the transmitter, and a sound collector and screen having a tubular extension fitting snugly on the tapered supporting member, as set forth.

55 4. In a device of the kind described, the combination with a telephone transmitter,

of a supporting member encircling the mouth piece of the transmitter and terminating substantially at the outer edge thereof, a sound collector and screen detachably fitting the supporting member, and a flange of non-acoustic material projecting inwardly from said screen with its free depending edge in proximity to the outer edge of said mouth piece, said flange being supported by said screen only at the outer periphery of said flange to permit the inner and unsupported edge thereof to extend inwardly beyond the edge of the mouth piece and into the path of sound travel, as set forth.

5. In a device of the kind described, a supporting member adapted to encircle the mouth piece of a telephone transmitter, a sound collector or screen which at its inner end fits over said supporting member, and its body portion is formed of substantially conical shape flaring outward from said transmitter; a yielding annular cushion attached at the outer end of said screen and adapted to conform closely to the face of the speaker; with one or more apertures formed in said outer or conical portion of said screen and leading directly into the inner chamber thereof for the admission of air therewithin, said apertures being provided with closures or shutters for varying the size of the air openings, as set forth.

6. In a device of the kind described, the combination with a supporting member adapted to encircle the mouthpiece of a telephone transmitter and having an inwardly extending flange adapted to fit under the mouthpiece, said member being tapered outwardly; of a sound screen of substantially conical form having at its smaller end a flaring extension corresponding to the taper of said supporting member and adapted to fit closely thereon; an annular face cushion overhanging inwardly at the outer periphery of said screen and attached to said screen by an elastic flange fitting over the same; and said screen having air apertures formed therein provided with shutters to vary the size of the air apertures; substantially as and for the purpose described.

In testimony whereof I affix my signature in the presence of two subscribing witnesses.

MARCUS P. FLACK.
